DOOR LATCH HANDLE

Henry Kartarik, White Bear Lake, Minn., assignor to
Ideal Security Hardware Corporation, St. Paul, Minn.,
a corporation of Minnesota

Filed Aug. 15, 1969, Ser. No. 18,717

Term of patent 14 years

Int. Cl. D8—03
U.S. Cl. D8—170

FIG. 1 is a view in perspective of a door latch handle, showing my new design;

FIG. 2 is a view in front elevation, on a reduced scale;

FIG. 3 is a view in side elevation;

FIG. 4 is a view in top plan; and

FIG. 5 is a view in bottom plan.

The side of the door latch handle opposite that shown in FIG. 3 is a mirror image of FIG. 3.

I claim:

The ornamental design for a door latch handle, as shown and described.
